UNITED STATES PATENT OFFICE.

EPHRAIEM CHAQUETTE, OF NEW ROCHELLE, NEW YORK.

CLAM FOR DREDGES.

SPECIFICATION forming part of Letters Patent No. 702,629, dated June 17, 1902.

Application filed February 25, 1902. Serial No. 95,613. (No model.)

To all whom it may concern:

Be it known that I, EPHRAIEM CHAQUETTE, a citizen of the United States, and a resident of New Rochelle, county of Westchester, State 5 of New York, have invented certain new and useful Improvements in Clams for Dredges, of which the following is a specification.

The object of my invention is to provide an improved clam for dredging purposes which 10 shall be more effective and simple in its operation than has heretofore been the case.

My invention relates to that class of clam which is opened and closed by means of compressed air, steam, or suitable gases, but may 15 also be operated hydraulically, if preferred.

To this end my invention consists in a shell composed of two hinged portions pivoted upon a suitable frame, a guide-rod mounted upon said frame, a cylinder loosely mounted upon 20 said guide-rod near one end and pivoted to one of said hinged portions of the shell, a piston loosely mounted upon said guide-rod near the other end and pivoted to the other hinged portion of the shell and adapted to work in 25 said cylinder, and suitable mechanism for admitting water, steam, compressed air, or gas to the cylinder on one side of the piston to open the clam and on the other side to close the same.

30 One form of my invention is shown in the accompanying drawings, in which—

Figure 1 is a side view. Fig. 2 is a front view. Fig. 3 is a top plan.

Same letters indicate similar parts in the 35 different figures.

A is the clam-frame, centrally supported by the ropes b b' b² from the pulleys c c' c², journaled in the upper part of the dredge-frame and coiled upon suitable drums (not shown) 40 located upon the dredge. The outer ropes b' b² are fastened to the outer ends of the cross-bar d, which forms part of the clam-frame A; but the middle rope b is connected to the slide e, which passes through said cross-bar 45 and is surrounded by the coiled spring f. This spring controls the admission of the compressed air, gas, steam, or water by means of which the clam is opened and closed. The pipe g, through which this admission takes 50 place, is coiled around the drum-pulley b³, which may be mounted on the same shaft with the pulleys c c' c² and turned with

them, as shown in Fig. 1, or upon an independent shaft, as shown in Fig. 2, in which case said shaft also carries the gear-wheel h, 55 which meshes with teeth h', provided for that purpose on the outer periphery of the pulley c.

The clam B is preferably of the hemispherical type, the two halves of which, C D, are 60 pivoted to the frame A near the center of the lower cross-bar i, as shown at j j. The clam is shown closed in the full lines of Fig. 2 and open in the dotted lines.

The opening and closing of the clam is 65 brought about as follows: Within the clam-frame A is situated a guide-rod k, carried by the arms l l', of which l' is adapted to slide freely longitudinally along the rod. A third arm l" hangs upon the rod k. A cylinder E 70 is attached to the arms l l', and the piston-rod F has its outer end journaled in the arm l". As the piston makes its backward and forward stroke in the cylinder the arm l' slips along the guide-rod from the position shown 75 in full lines to that shown in dotted lines, or vice versa. Simultaneously with this sliding motion the guide-rod, cylinder, and piston move bodily up or down without interfering with their relative horizontal position by 80 reason of their attachment to the hinged halves of the clam-shell, as hereinafter described.

The cylinder E is provided with the two inlet-ports m m' and with suitable exhaust 85 ports. (Not shown.) The port m is connected by a tube n to a three-way cock o, while the port m' is similarly connected therewith by the tube n'. The movements of this three-way cock are determined by the spring 90 f as follows: When the tension of said spring is relaxed by the slackening of the center rope b, the three-way cock is so turned that compressed air or other motive fluid entering through the tube g is directed through the 95 pipe n and port m against the piston inside the cylinder E and, driving the same before it, causes the piston-rod F to make its inward stroke. When the spring f is contracted by the tightening of the rope b, the motive fluid 100 entering the three-way cock o through the pipe g and branch pipe g' is directed through the tube n' and port m' into the cylinder E and causes the piston-rod F to make its re-

turn stroke. These in and out strokes are utilized for the opening and shutting of the clam as follows: The arm l^2 , which bears the piston-rod, is swiveled at p to the outer end 5 of the half C of the clam B, while the cylinder E carries a lug q , which is swiveled at p' to the other half, D, of the clam. The in-stroke of the piston tends to draw up the outer end of the half or hinged portion of the 10 shell C, to which the arm l^2 is swiveled. As this cannot take place without raising bodily 15 the piston and everything attached to it, owing to the fact that the hinged portion C swings radially from the point j on the fixed bar, it follows that the cylinder E and the 20 things attached thereto, including the other hinged portion of the shell D, must rise at the same time. In this way the arms l^1 and l^2 draw toward each other along the guide-rod 25 k as the piston-rod f enters the cylinder E and the whole structure, as it were, climbs the clam-frame to the position shown in dotted lines, by which time the clam is wide open. The reverse operation takes place

when the supply of motive fluid is shifted to the other side of the piston and the clam closes into the position shown in full line.

It is to be understood that the clam goes down into the water open, gets its load in clos-

ing, goes up closed, and is opened again at 30 any desired height to discharge its contents into a scow or other receptacle placed to receive it.

To insure the winding and unwinding of the feed-pipe g without interfering with the 35 proper feeding of the motive fluid is fed to the pipe g through the journal-box r from the pipe s , connected with a reservoir. (Not shown.)

I claim—

The above-described clam for dredges which consists of a shell composed of two hinged portions pivoted upon a suitable frame, a guide-rod mounted on said frame, a cylinder mounted upon said guide-rod and pivoted to 45 one of said hinged portions of the shell, a piston adapted to work in said cylinder and an arm loosely mounted on said guide-rod near the other end and pivoted to the other hinged portion of the shell, the said arm supporting 50 the outer end of said piston, and means substantially as described for operating said piston-rod, so as to open and close said clam.
